UNITED STATES PATENT OFFICE.

GEORGE G. BELDEN, OF SPOKANE, WASHINGTON.

FLOAT-OPERATED INDICATOR.

1,271,008.

Specification of Letters Patent.

Patented July 2, 1918.

Application filed August 12, 1916. Serial No. 114,564.

To all whom it may concern:

Be it known that I, GEORGE G. BELDEN, a citizen of the United States, residing at Spokane, in the county of Spokane and State of Washington, have invented certain new and useful Improvements in Float-Operated Indicators; and I do hereby declare the following to be a full, clear, and exact description of the invention, such as will enable others skilled in the art to which it appertains to make and use the same.

This invention relates to float operated indicators of the type particularly designed for use in connection with explosive engines for indicating the quantity of oil contained in the crank case.

The invention has for its object to provide an improved indicator including a float housing which is suspended from the upper part of the crank case of the engine and is entirely independent of the bottom part so as to permit the latter to be readily removed when necessary.

Another object is to generally improve and simplify indicators for explosive engines and render them practical and efficient and also readily adaptable to numerous types of explosive engines.

With these and other objects in view, the invention consists in the novel construction, combination and arrangement of parts as will be hereinafter specifically described, claimed and illustrated in the accompanying drawing, in which:

Fig. 1 represents a side elevation of an explosive engine, partly in section, illustrating the improved indicator applied thereto,

Fig. 2 represents an enlarged fragmentary sectional view through the crank case of the engine, illustrating a portion of the indicator in detail,

Fig. 3 represents an elevation of the indicating part of the indicator,

Fig. 4 represents a front elevation, similar to Fig. 3, illustrating a modified type of the indicator, and

Fig. 5 represents a longitudinal sectional view through the upper terminal of the bendable guide for the flexible operating element.

Referring to the drawing in detail, wherein similar reference numerals designate corresponding parts throughout the several views, the numeral 5 indicates generally a well known type of explosive engine including the usual upper and lower crank case

sections 6 and 7, respectively, the lower section 7 being detachably secured to the upper section 6 in order that access may be had to the connecting rod and crank shaft bearings. 60 In the accompanying drawing the invention is shown as applied to a motor vehicle, the dash board 8 of which is represented in Fig. 1.

The improved indicator comprises a float 65 housing 9, having oil ports 10 adjacent the lower end and an inwardly directed flange 11 formed at the lower edge thereof to prevent the float 12, which is arranged within the housing from dropping therefrom when the 70 bottom section 7 of the crank case is removed. The flange 11 of the housing simply rests upon the bottom section of the crank case and is entirely independent thereof so as to permit the bottom section to be detached independently of the float housing.

A cover 13 is removably fitted over the upper open end of the housing 9 and is formed with an integral flange 14, which is rigidly and permanently secured to the 80 lower terminal of a tubular guide 15. The guide 15 is preferably formed of bendable metal and is extended upwardly through an aperture in the top part 6 of the crank case.

A ring 16 is fastened to the top section 6 85 and is formed with an integral flange 17 receiving the tubular guide 15. A set screw 18 is fitted in an internally screw threaded aperture formed in the flange 17 and engages the tubular guide 15, whereby the housing 9 90 is suspended from the top crank case section, and is held in position after the removal of the bottom crank case 7.

The tubular guide 15 is extended to the dash board or other convenient point upon 95 the motor vehicle or other object and is connected with a tube 19 having a slot 20 therein. A sight glass tube 21 is confined in the tube 19 between the terminal of the guide 15 and a plug 22 fitted in the upper end of the 100 tube 19.

A stem 23 is connected with the float 12, extends upwardly within the lower terminal of the guide 15 and is rigidly secured at its upper terminal with the adjacent end of 105 the flexible actuating member 24. The opposite terminal of the flexible member 24 is extended into the transparent tube 21 and is provided with an indicating head 25, which is visible through the slot 20 in the tube 19 110 and may be used or referred to in connection with markings on a plate 26 fastened in

front of the tube 19 to indicate the quantity of oil contained in the lower section 7 of the crank case.

In the modification of the invention illustrated in Fig. 4 the end of the flexible member 24 is connected with a rod 27, having a line marked thereon adapted to be read in connection with the markings on the plate 26 to accurately indicate the quantity of oil in the crank case of the engine.

What I claim is:

1. In combination, an oil indicator adapted for use in connection with an engine crank case of the sectional oil-containing type comprising an upper and a lower section, an actuating float for the indicator and adapted for location in the crank case, a housing for said float having an apertured lower terminal, an inwardly directed flange at the lower terminal of the housing, preventing displacement of the float and con-

stituting a supporting base adapted to movably engage the bottom of the lower section of the crank case, and means for adjustably suspending the housing from the upper section of the crank case independently of the lower section thereof. 25

2. In combination, an engine provided with a crank case, said crank case including an upper section and a lower section detachably secured thereto, and an oil indicator suspended from the top crank case section and being independent of the lower detachable section, whereby the latter may be removed independently of the indicator to expose the internal mechanism thereof. 30 35

In testimony whereof I affix my signature in presence of a witness.

GEORGE G. BELDEN.
